UNITED STATES PATENT OFFICE.

CONSTANTIN SCHMIDTLEIN, OF BERLIN, GERMANY, ASSIGNOR TO JOHANNES MOSER, OF BERLIN-SCHÖNEBERG, GERMANY.

PIANO SOUNDING-BOARD.

SPECIFICATION forming part of Letters Patent No. 635,872, dated October 31, 1899.

Application filed October 29, 1897. Serial No. 656,791. (No model.)

To all whom it may concern:

Be it known that I, CONSTANTIN SCHMIDTLEIN, a citizen of the Empire of Germany, and a resident of Berlin, Germany, have invented 5 certain new and useful Improvements in Sounding-Boards, of which the following is a specification, reference being had to the accompanying drawing, forming part thereof.

The object of the present invention is to 10 construct a ribless sounding-board having sufficient strength to sustain the pressure of the strings of the musical instrument to which it is fitted and capable of vibrating in such a way as to render a sound rich in harmonics 15 and equally respond to each of the strings.

The annexed drawing shows my improved sounding-board in section—that is to say, so much as is necessary for explaining this invention. 20 The board is formed of two layers of wood *a* and *b*, crossing one another in the direction of the grain of the wood, and it is thickest in the middle and diminishes toward its supporting-frame *A*. Such a construction is 25 intended principally to afford strength, while maintaining a substantial equality of strain over the whole extent of the board.

Immediately before the place where this board has bearing on its support *A* the thickness of the board is diminished to a greater 30 amount than corresponds to the gradual tapering of the whole extent of the board—that

is to say, it is more steeply diminished by making in its surface a shallow groove in each face. By this means the vibratory qualities of the sounding-board are improved. 35

I do not claim, broadly, to make a sounding-board out of a plurality of thicknesses of wood with the grain crossing, nor to make a sounding-board thicker under the bridge; but 40

What I claim is—

1. A ribless sounding-board the thickness of which is greatest in the center and tapers gradually thence toward a line parallel to and near to its edges where it is more sharply 45 reduced in thickness immediately before the part adapted to be fixed on its support.

2. A ribless sounding-board composed of two layers of wood with their grain crossing one another, the thickness of which board is 50 greatest in the center and tapers gradually thence toward a line parallel to and near its edges where each face of the board is provided with a shallow groove constituting a sharper diminution immediately before the 55 part intended for attachment to the support of the sounding-board.

In witness whereof I have signed this specification in presence of two witnesses.

CONSTANTIN SCHMIDTLEIN.
